UNITED STATES PATENT OFFICE.

FRANK W. MERRICK, OF SOMERVILLE, MASSACHUSETTS.

SEWING-MACHINE.

SPECIFICATION forming part of Letters Patent No. 388,897, dated September 4, 1888.

Application filed March 7, 1887. Serial No. 229,953. (No model.)

To all whom it may concern:

Be it known that I, FRANK W. MERRICK, of Somerville, county of Middlesex, State of Massachusetts, have invented certain new and useful Improvements in Sewing-Machines, of which the following is a specification, reference being had to the drawings accompanying and forming a part hereof, in which—

Figure 1 is a front elevation of the post of the machine with the front plate removed, showing the needle-operating mechanism with my improved cast-off attached. Fig. 2 is a partial sectional side view of the same. Fig. 3 is an elevation similar to Fig. 1, but showing the parts in another position. Fig. 4 is a detail view to illustrate a modification.

The object of my invention is the construction of an improved cast-off mechanism for sewing-machines; and it consists in the constructions and combinations of parts specified in the claims at the end of this specification, whereby a cast-off which is arranged rearwardly of the hooked needle (or on the side of the needle opposite its hook) will be caused to pass forward through the loop of the needle-thread to disengage the same from the hook of the needle and hold it in position for the needle to pass freely downward through it with the next succeeding loop.

My invention may be applied, as will be obvious, to sewing-machines of various styles, and I have not, therefore, deemed it necessary to show in the drawings anything more than the parts of a machine to which my improvement is directly applied. The needle-post and needle-bar are shown as patented by me, Letters Patent No. 343,383, dated June 8, 1886.

A represents the frame of the machine, which carries the work-plate a. The needle-post B is pivoted at its lower end on a rocker shaft, b, and is given a vibratory movement by means of a cam and yoke situated behind it, as will be more fully understood by reference to my said patent.

D is the needle-bar, which carries the needle d and which slides in a slot or groove in the needle-post and is actuated by a link, f, pivoted thereto at its upper end and at its lower end pivoted to a disk, E, fast to the lower or main shaft of the machine.

For the purpose of carrying and actuating

the cast-off k, I have provided a cast-off carrier or piece, H, which is provided with a vertical slot, j, through which the pivot-pin e of the needle-bar passes. The slot j is somewhat less in length than the throw of the needle-bar, so that at the extreme of its downward throw the pivot-pin e comes in contact with the lower end of the slot and moves the cast-off barrier, retracting the cast-off and allowing it to slip the loop. A projection, m, at the lower end of the cast-off carrier H is connected by a spiral spring, n, with a pin on the needle-post, and the tension of this spring serves to raise the cast-off carrier whenever the pivot-pin e has begun its upward movement with the needle-bar. (See Fig. 3.) When the cast-off is retracted, its point lies to the rear of the line of the needle and directly behind the loop when the needle is at its lowest point. It is necessary, therefore, that the cast-off should move upward and forward, carrying its point directly across the line of the needle. To obtain this movement, the cast-off carrier H is provided with the oblique slot p, through which a pin, r, passes into the needle-post. When the cast-off is retracted, its bar H is down and back in the position shown, Fig. 1, and when it is up and forward the pin r is at the bottom of the slot p, and the parts assume the position shown, Fig. 3. The cast-off carrier works on the face of the needle bar and post, and it is necessary to offset the cast-off and make it of the shape shown in Fig. 2 in order that its point may cross the line of the needle. The cast-off is also bent forward and upward in the manner shown in Fig. 1. By giving the cast-off this shape and moving it in the direction described its point moves at right angles, or substantially so, to the position of the loop when the needle is at its lowest point, (see Fig. 1,) thus enabling it with greater facility and certainty to pass into the loop. After entering the loop its movement is across the track of the needle and to a certain extent upward, with the needle thus surely disengaging the thread from the hook.

In the modification of my invention shown in Fig. 4 the cast-off bar H, instead of having the inclined slot p, is connected by a link, t, pivoted at a to the cast-off bar and at b' to the needle-post, as B, Figs. 1 and 2, and the said

cast-off bar is in sliding contact with the needle-bar and is operated by the pin *e*, moving in the slot *j*, as in the other form of my invention. It will thus be apparent that when the 5 said cast-off bar is raised (by contact of the pin *e* with the upper wall of the slot *j* or otherwise) the cast-off will be moved forward, as shown in dotted lines to cause its point to pass into the loop of needle-thread to disengage the 10 loop from the hook of the needle, the operation of this modification of my invention being thus essentially the same as the form of my invention first described.

It will be observed that with both forms of 15 my invention herein shown the cast-off carrier has a sliding connection with the needle-bar or needle-post, so that the said cast-off carrier reciprocates up and down bodily, while its upper end has a back-and-forth or vibratory movement to cause the offset upper end of the cast-off to cross the path of the needle to take the loops of thread from the hook of the latter. In the machine shown by my former patent, No. 343,383, the cast-off had an 25 offset-point which crossed the path of the needle; but as the cast-off carrier was pivoted, so that it could not move endwise bodily, a greater throw was required for the needle than is necessary in the present instance to enable the 30 cast-off to remove the loops properly.

What I claim is—

1. In a sewing-machine, a hooked needle, its operating mechanism, and a cast-off arranged adjacent to said needle and on the same side 35 of the work-plate that the needle is, said cast-off being also rearward of the needle (or on the side thereof opposite its hook) and being bent or offset to have its point extend to the line in which the needle reciprocates, combined

with a reciprocating and vibrating cast-off 40 carrier also on the same side of the work-plate that the needle is, and having a sliding or endwise movement relative to the needle-bar or carrier, and mechanism for operating said cast-off carrier to impart endwise and vibrating 45 movements thereto, whereby as the cast-off moves bodily forward and upward its point will be caused to cross the path of the needle and take a loop of thread from the hook thereof, substantially as set forth.

2. In a sewing-machine, a hooked needle, its operating mechanism, and a cast-off arranged rearward of the said needle, (or on the side thereof opposite its hook,) the point of said cast-off being bent or offset to extend to the 55 path of the said needle, combined with a carrier for the said cast-off arranged adjacent to the needle-bar and provided with an oblique guiding-slot near its upper end, a pin to enter said slot, and means for reciprocating said 60 carrier to cause the point of the cast-off to cross the path of the needle and take a loop of thread from the hook thereof as the cast-off moves bodily forward and upward, substantially as set forth.

3. The combination, with the hooked needle *d*, the needle-bar *D*, the pin *e*, by which the said bar is reciprocated, and means for actuating said pin, of the cast-off *k*, the cast-off carrier *H*, having the vertical slot *j* and the 70 oblique guiding-slot *p*, the relatively-stationary pin *r*, arranged in said oblique slot, the spring *n*, the link *f*, and the crank, substantially as set forth.

FRANK W. MERRICK.
